WEATHERPROOF ANNUNCIATOR CASE.
APPLICATION FILED FEB. 25, 1913.

Patented June 29, 1915.

2 SHEETS—SHEET 2.

UNITED STATES PATENT OFFICE.

ALBERT STERN, OF YONKERS, AND PHILIP K. STERN, OF NEW YORK, N. Y.; SAID
PHILIP K. STERN ASSIGNOR TO SAID ALBERT STERN.

WEATHERPROOF ANNUNCIATOR-CASE.

1,144,871.

Specification of Letters Patent. Patented June 29, 1915.

Application filed February 25, 1913. Serial No. 750,610.

To all whom it may concern:

Be it known that we, ALBERT STERN and PHILIP K. STERN, respectively subject of the King of Great Britain and citizen of the United States, and residents of the city of Yonkers, in the county of Westchester, and of the city of New York, in the county of New York, and both of the State of New York, have invented a new and Improved 10 Weatherproof Annunciator-Case, of which the following is a full, clear, and exact description.

Our invention relates to cases for annunciators of the electrical type and has reference more particularly to cases for annunciators for signaling the anticipated movement of a motor vehicle.

An object of the invention is to provide a convenient, neat, strong, simple and inexpensive case.

Another object of the invention is to provide a weather-proof case which can be easily and quickly assembled or taken apart without in any way injuring the weather-proof qualities of the case.

We attain these objects by a structure conveniently illustrated in the accompanying drawings forming a part of the specification, in which similar characters of reference indicate corresponding parts in all the views and wherein—

Figure 1 is a front elevation of a case embodying the invention and a support therefor; Fig. 2 is an end elevation thereof in the direction of the arrow 2, shown in Fig. 1; Fig. 3 is a view similar to Fig. 2 without the support therefor, and partly in section, to show the details of construction; Fig. 4 is an end view, similar to Fig. 3, of a fragment 40 of the case, partly in section, illustrating the manner in which the window is secured or removed from the case; Fig. 5 is an enlarged sectional view on lines 5—5, Fig. 3; and Fig. 6 is a section taken through the case on line 6—6 of Fig. 3, one end only of the case being illustrated.

Referring to the drawings, 1 represents a shell, which is preferably tubular. A part of the lateral surface of said shell is raised 50 to form a laterally protruding, substantially rectangular prism 2, the end of which has a rectangular opening 11 bordered by portions 3, 4, 5 and 6 of the end of the prism and forming the sashes of the window for the shell. The raised, apertured, rectangular

prismatic portion 2 forms a window for the shell 1 and extends nearly from end to end of the shell, its width being slightly less than the diameter of the shell. Closing the aperture in the end of the prismatic portion 60 2 is a pane of glass 21 which contacts with a gasket 22 positioned intermediate the glass and the sashes 3, 4, 5 and 6. The pane of glass is maintained against the gasket by means of a plurality of resilient clamping 65 members 15, either carried by strips 12 suitably secured to the substantially horizontal sides of the prismatic portion 2, or by securing said resilient clamping members directly on to the mat or bezel 23 which fits 70 between the clamping member 15 and the pane of glass.

As shown in the drawing, the clamping members 15 are rotatably mounted on the strips 12 which are provided with studs 14 75 forming a stay for locking the clamping members 15 when the same locks the pane of glass in the prismatic portion 2 and therewith the gasket and the bezel. When the clamps 15 are carried by the bezel, the stud 80 14 is secured to the substantially horizontal sides of the prismatic portion 2. In either case, said clamping means 15 removably connect the pane of glass in the prismatic portion 2. Fig. 4 illustrates the inoperative 85 position of the clamping members 15 when the pane of glass 21 is fitted into the prismatic portion 2 or removed therefrom.

The shell 1, at the left end when facing the window, is provided with a disk 29 permanently secured thereto in any suitable way. To the other end of the shell is rigidly secured a ring 32 having an oblated lateral surface formed by an extension 33 (see Figs. 3 and 6). The end of the ring engaging the shell is provided with an integral portion 34 which has an inwardly depressed annular recess 35 concentric with the symmetrical part of the ring. The recess 35 is rigidly secured to a neck 30 formed by reducing the 95 end of the shell. The inner diameter of the shell at the neck is slightly larger than the width of the prismatic portion 2 and where-through the pane of glass and the means for securing the same are introduced. A cap 37 is made to fit snugly into the ring 32. A portion 40 of said cap extends over the extension 33 of the ring and forms an elbow reinforced by a hollow rib 39. A tubular arm 41, preferably angular in cross section, 100 105 110

- is secured into the elbow 40. Said arm 41 extends parallel to the shell and is removably secured by means of a clamp 45 forming part of a column 43 which forms the support for the case. The hollow of the rib 39 forms a duct 42 which registers with the tubular arm 41 and wherethrough are passed the means for controlling the contrivances in the case.
- 10 From the above description it will be seen that the case herein described possesses all the weather-proof qualities, in view of the fact that the window aperture 11 is properly sealed by the resilient means which lock the glass against the sashes, with a gasket 22 intermediate the sashes and the glass, and also the bezel lying behind the glass to give a neat appearance and provide a better locking means for the glass within the prismatic portion of the shell. The cap 37, which is telescopically mounted on the ring 32 fits tightly thereon and perfectly closes the end of the case wherethrough the glass and its appurtenances for securing the same are introduced.
- 15 20 25 The means for controlling the device within the case is introduced through the duct on the hollow arm, which can be plugged afterward, thus making a perfectly weather-proof case.
- 30 Having thus described our invention, we claim as new and desire to secure by Letters Patent:
1. In a case of the character described, a shell having an integral end; an oblated ring secured to the other end; a cap provided with a carrying arm and adapted to telescopically engage the oblated ring whereby the arm is spaced from the lateral surface of the shell.
- 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770
2. In a case of the character described, a shell having a closed end and a rectangular, substantially prismatic apertured, protruding portion on the lateral surface thereof; a pane of glass in said prismatic portion screening said opening; and a cap having a carrying arm removably associated with the open end of the shell.
3. In a case of the character described, a tubular shell having a protruding, rectangular, substantially prismatic portion, including means forming a window for said shell, said shell being closed at one end; and a removable cap associated with the other end, said cap having a tubular carrying arm ex-

tending parallel to the shell and a duct there- 55 in registering with the other arm, whereby access may be had to said case through the arm and duct.

4. In a case of the character described, a shell having a closed end and a rectangular, 60 substantially prismatic, apertured, protruding portion on the lateral surface of said shell; a pane of glass in said prismatic portion adapted to screen said aperture; resilient means associated with said pane of glass 65 and prismatic portion for locking said pane of glass therein; an oblated ring associated with the open end of the shell; a cap fitting into said ring and having an extension exterior of said ring forming an elbow; and a 70 tubular arm carried by said elbow, said cap having a reinforcing, hollow rib registering with said tubular arm whereby access may be had to the case.

5. In a case of the character described, a 75 tubular shell closed at one end and having a rectangular, substantially prismatic, apertured portion on the lateral surface of the shell; a glass screening said aperture and forming a window for said shell; a ring 80 rigid with the open end of the shell and having an oblated, lateral surface formed by an extension lateral of said shell; a cap fitting snugly into said ring and removably associated therewith, said cap having an extension 85 forming an elbow above the extension of the ring forming the oblated surface; a tubular arm carried by said elbow of the cap; and a hollow rib reinforcing the cap and forming a duct from the tubular arm into the case, 90 whereby access may be had into said case.

6. In a case of the character described, a shell closed at one end and having a glass-screened lateral opening, a cap removably associated with the other end of the shell, 95 said cap having a duct, a hollow supporting arm extending parallel to the lateral surface of the shell and registering with the duct wherethrough access may be had to the case, said arm being spaced from the lateral 100 surface of the shell, and a support clamping said arm at the shell.

Signed this 24th day of February, 1913.

ALBERT STERN.

PHILIP K. STERN.
